DESIGN FOR A CHILD'S PLAY WAGON

Carroll E. Dodson, Kansas City, Mo.

Application September 17, 1943, Serial No. 111,144

Term of patent 3½ years

To all whom it may concern:

Be it known that I, Carroll E. Dodson, residing at Kansas City, in the county of Jackson and State of Missouri, have invented a new, original, and ornamental Design for a Child's Play Wagon, of which the following is a specification, reference being had to the accompanying drawing, forming part thereof, in which

Fig. 1 is a front perspective view of a child's play wagon, showing my new design;

Fig. 2 is a top perspective view; and

Fig. 3 is a bottom perspective view thereof.

I claim:

The ornamental design for a child's play wagon, substantially as shown.

CARROLL E. DODSON.
